UNITED STATES PATENT OFFICE.

JOSEPH WOLFF, OF BROOKLYN, NEW YORK, ASSIGNOR, BY MESNE ASSIGNMENTS, TO SONORA PHONOGRAPH COMPANY, INC., A CORPORATION OF NEW YORK.

CONCEALED LOUD SPEAKER FOR RADIO RECEIVING SETS.

Application filed April 12, 1924. Serial No. 705,980.

This invention relates generally to a loud speaker for radio receiving sets, and more particularly to a concealed loud speaker.

One of the objects of this invention is to provide a supplemental cabinet unit having a sound amplifying member with a sound passage therethrough, said cabinet unit being adapted for, and capable of, being associated with any of the well-known receiving sets now on the market. The loud speakers now in use generally employ a horn separate and apart from the radio receiving set, which is large, unsightly, and frequently takes up so much room that it is in the way; I have, therefore, constructed a cabinet which may be employed as a supplemental cabinet to a radio receiving set or which may be affixed to the radio receiving set in a separate compartment and thus conceal the horn. The concealed horn, whether combined with the radio receiving set or in a supplemental cabinet, tends to economize space and at the same time provide means for greatly improving the reproduction and amplification of the sound.

Another object of the invention is to provide an improved loud speaker in cabinet form, which will be compact, simple in construction, economical to manufacture efficient in operation, and attractive in appearance.

Another object of the invention is to provide a loud speaker horn compact in form, efficient in operation and adapted for use in a cabinet.

A further object is to provide a cabinet and a separate horn to be placed therein and to cooperate therewith to give improved loud speaker effects substantially free from distortion.

A further object of the invention is to provide means of the character herein described, simple in construction, thoroughly reliable and efficient in its purpose, positive in operation, and inexpensive to manufacture.

With these and other objects in view to be more fully set forth hereinafter, the invention consists in the novel construction, combination of elements, and arrangement of parts which will be exemplified in the construction hereinafter described in the specification and illustrated in the accompanying drawings considered together or separately.

The inventive idea involved is capable of receiving a variety of mechanical expres-

sions, one of which for the purpose of illustrating the invention, is shown in the accompanying drawings.

The invention will be first described in connection with the accompanying drawings illustrating one embodiment of my invention, wherein similar reference characters are used to designate corresponding parts throughout the several views, and then more specifically defined and indicated in the appended claims.

In the drawings—

Fig. 1 is a sectional top plan view showing a loud speaker horn in position in the cabinet.

Fig. 2 is a view in front elevation, part of the grille being broken away.

Fig. 3 is a rear elevation of the horn, partly in section.

Fig. 4 is a view in front elevation showing the loud speaker attached to a radio receiving set.

In the illustrated embodiment of the invention, the loud speaker 10 comprises a horn 11 and a cabinet 12 therefor which comprises a base 13 provided with feet 14 adjacent the four corners thereof. The cabinet 12 also comprises left and right side walls 15 and 16 respectively, a rear wall 17, and a top 18. To protect the horn and to give an attractive appearance to the front of the cabinet, provision may be made for a removable grille 19, which fits between the side walls 15 and 16, and to hold the grille in position, provision may be made for a shallow groove 20 in the base and for a groove 21 in the top 18 of the cabinet. The upper edge of the grille may be inserted in the groove 21 and its lower edge swung rearwardly into position to allow it to be lowered into the groove 20, the upper edge of the grille then assuming the position indicated by the dotted line 22 at the top of Fig. 2.

The loud speaker horn 11 has a mouth substantially co-extensive with the opening at the front of the cabinet 12 and has a horizontal lower wall 23 extending substantially to the rear of the cabinet, said wall having supports 23^a—23^b which hold it in a suspended position from the outer casing. Such suspension of the loud speaker horn 11 will improve the reproduction and amplification and make the speaker substantially free from distortion. The left and right walls 24 and 25 respectively converge rearwardly, the left

wall 24 terminating at a point 26 and the right wall 25 being curved gradually to the left (Fig. 2) to a point 27. As shown in Fig. 3, the upper wall 27 of the horn is brought downwardly rather abruptly from its front edge and given a gradual curve rearwardly to a substantially horizontal direction at the point 28.

At the points 26, 27 and 28 the walls 24, 25 and 27 merge into the sides of a passage 29 in a block 30, the passage 29 being curved gradually to a vertical direction at the top of the block 30 where it communicates with a passage 31 in an extension 32 which corresponds to the tone arm of a phonograph. The extension 32, which may be connected with the block 30 by any suitable means such as screws 33, gradually decreases in size and has attached thereto a phone attachment 34 which may be of the well known Baldwin type. The attachment 34 has a diaphragm 35 and a head 36 provided with an opening 37 opposite the center of the diaphragm 35, and with a sleeve 38 for attachment to the end of the extension 32 by suitable means such as a set screw 39.

To connect the loud speaker 10 with a radio receiving set 40 (Fig. 4), provision is made of two conductors 41 and 42 connected with the attachment 34 at 43 and having an insulating covering 44 extending along the greater part of the length thereof. Preferably, provision is made for an opening 45 in the base 13 of the casing and the conductors 41 and 42 with their casing 44 extend downwardly from the attachment 34, through such opening, and away from the cabinet for connection with the radio receiving set. For such connection the conductors 41 and 42 are provided with plugs 46 and 47 respectively to fit into suitable sockets (not shown) in the receiving set 40.

As indicated in Figs. 1, 2 and 3, the horn 11 is supported on the base 13 of the cabinet 12 by means of feet 23^a at the front, and a foot 49 at the rear, the feet 23^a and 49 being of suitable material such, for example, as felt or rubber. It will also be seen that the horn 11 is spaced from the cabinet at all points. It has been found that, with a horn of the form described and positioned in the cabinet as indicated, exceptionally good and improved results will be obtained, and distortion prevented.

In the embodiment of the invention illustrated, the cabinet and the horn, with the exception of the metal tone arm 32, are made of wood, but I wish it distinctly understood that my invention is not to be so limited.

It will be obvious from the foregoing that I have invented a very unique and novel concealed horn radio loud speaker in which the loud speaker is concealed within the casing and suspended therein, said loud speaker being supported on the base and in no man-

ner being in contact with the walls of the casing. I find that a device so constructed produces exceptional and improved sound reproduction, free from distortion.

In accordance with the provisions of the patent statute, I have described the principle of my invention, together with the apparatus which I now consider to represent the best embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and the new results accomplished, as herein set forth, as it is obvious that the particular embodiment herein shown and described is only one of many that can be employed to attain these objects and accomplish these results.

Having now described my invention, what I claim and desire to secure by Letter Patent is:

1. In a device of the character stated, a sound amplifier including a rear inlet portion extending horizontally and thence downwardly, said inlet and downwardly extending portion being of gradually increasing area in cross section, a front exit portion extending forwardly from said horizontal rear inlet portion at substantially an angle thereto and having a rear vertical side wall against which said downwardly extending inlet portion discharges, outwardly diverging vertical walls and an upwardly diverging top wall for said exit portion through which the reproduced sounds are discharged, and means for securing said rear inlet and front exit amplifier portions in assembled position.

2. In an acoustic device, a sound amplifier having a rear amplifier part extending horizontally and thence downwardly, said part being of gradually increasing area in cross section, a front amplifier part extending forwardly from said rear amplifier part at substantially a right angle to said horizontal rear amplifier part and having a rear side wall against which said downwardly extending amplifier part discharges, and outwardly diverging vertical side and top walls through which the reproduced sounds are discharged, said rear horizontal inlet part being of a length not exceeding the front amplifier part of said amplifier and being in proximity to the rear outer surface of said amplifier.

3. In a device of the character stated, a sound amplifier having a rear amplifier part which part is of gradually increasing area in

cross-section, a front amplifier part positioned at right angles to said rear amplifier part the latter being disposed horizontally above the rear walls of the front amplifier part, the walls of which are converging and extend downwardly and thence inwardly towards the side wall of the rear portion of the base of said front amplifier part against which the sound waves impinge upon entering said front amplifier part, and outwardly diverging side and top walls for said front amplifier part.

4. In a device of the character stated, a

sound amplifier having a rear portion having an inlet end and an enlarged exit end, the 15 said inlet end merging into a laterally extending branch, the latter merging into a downwardly and inwardly extending branch, a front exit amplifier portion located below the lateral branch of said amplifier portion 20 and having its inlet end connected with the enlarged exit end of said rear portion.

This specification signed this 10th day of April, 1924.

JOSEPH WOLFF.
